UNITED STATES PATENT OFFICE.

JAMES S. WHITNEY, OF WALLINGFORD, PENNSYLVANIA.

DESIGN FOR A CAR-WHEEL.

SPECIFICATION forming part of Design No. 27,554, dated August 17, 1897.

Application filed December 1, 1896. Serial No. 614,134. Term of patent 14 years.

To all whom it may concern:

Be it known that I, JAMES S. WHITNEY, a resident of Wallingford, Delaware county, Pennsylvania, have invented and produced a new and original Design for Car-Wheels, of which the following is a specification.

The design is shown in the accompanying drawings, in which—

Figure 1 is a plan view of a car-wheel embodying the design, and Fig. 2 is a transverse sectional view of the same.

A is the hub, and B is the rim, of the wheel.

C C are double plates extending inwardly from the outer edges of the rim for a short distance and uniting in the annular web D, which extends up to the hub A. The double plates C C form, with the rim B, the annular triangular space E.

The web D extends from the union of the plates C C to the hub A and is located entirely within the planes of the two faces of the wheel, so as not to project or extend beyond the plane of either face. It inclines

slightly toward the inner or projecting portion of the hub.

F F are ribs on either or both faces of the web D between the hub A and plates C C. They may, however, be omitted without departing from the design, the essential feature of which resides in the web D uniting the hub A and plates C C when so located as to lie wholly within the space bounded by the planes of the faces of the wheel, so as not to project beyond the plane of either face.

Having now described the design, what I claim as new, and desire to secure by Letters Patent, is—

The design for a car-wheel substantially as described and as shown in the accompanying drawings.

In testimony of which invention I have hereunto set my hand.

JAMES S. WHITNEY.

Witnesses:

ERNEST HOWARD HUNTER,
R. M. KELLY.
